(57) **CLAIM**

The ornamental design for a frozen pop maker, as shown and described.

DESCRIPTION

FIG. 1 is a perspective view as seen from the top, front and right side of a frozen pop maker showing the new design; FIG. 2 is a front view thereof, the front and rear view being mirror images;

FIG. 3 is a right side view thereof, the right and left side views being mirror images; and,

FIG. 4 is a top view thereof.

The broken lines in the drawings illustrate the portions of the design that form no part of the claim.
